United States Patent Office

Des. 183,277

Patented July 29, 1958

183,277

WALL SHELF

Richard E. Duchin, New York, N. Y., assignor to Maurice Duchin Creations, Inc., New York, N. Y., a corporation of New York

Application November 18, 1957, Serial No. 48,520

Term of patent 14 years

(Cl. D33—3)

I claim:

The ornamental design for a wall shelf, as shown.
